UNITED STATES PATENT OFFICE.

EDWARD J. VAUDREUIL, OF EAU CLAIRE, WISCONSIN.

PROCESS OF SNIPPING BEANS.

1,351,088.

Specification of Letters Patent. Patented Aug. 31, 1920.

Original application filed March 12, 1917, Serial No. 154,104. Divided and this application filed May 28, 1917, Serial No. 171,405. Renewed January 15, 1920. Serial No. 351,557.

To all whom it may concern:

Be it known that I, EDWARD J. VAUDREUIL, a citizen of the United States, residing at Eau Claire, in the county of Eau Claire and 5 State of Wisconsin, have invented certain new and useful Improvements in Processes of Snipping Beans, of which the following is a specification.

My invention relates to a process of snipping beans to prepare the same for canning. 10 It is the object of my process to operate continuously upon bean pods so that the ends thereof will be automatically snipped or removed and thus prepare the pods for canning or other culinary purposes. The process is carried out in the following manner. The pods are first assorted into a number of lots, the pods of each lot being of substantially uniform size and the pods in 15 one lot being of a different size from those in the other lots. The pods are then continuously fed to a supporting member formed with a multiplicity of apertures of a size adapted to receive the ends of the pods 20 of the particular assortment to be snipped, so that said ends will protrude through the supporting member when they pass into the aperture. The pods are then continuously agitated and turned and dropped upon the 25 supporting member and removed therefrom so that the ends of the pods will be presented to the supporting member many times and both ends will ultimately enter apertures and protrude through the supporting 30 member. The supporting member with the protruding pods is then moved relatively to a shearing device in proximity thereto, and in this manner the ends of the pods protruding through the aperture below the supporting member will be sheared or snipped off.

Different forms of apparatus may be employed for carrying out my process. Any 45 form of mesh device or apertured supporting member may be employed and the agitating of the pods may be effected manually or by any suitable mechanism. The essential part of this step is that the pods shall be lifted and turned and dropped, and that 50 during the dropping they shall be acted upon so as to be caused to strike upon the apertured support in a substantially vertical position, thus insuring that the ends of the pods will be presented many times for entrance through apertures so that before the

60 pods finally leave the supporting member both ends thereof will have had opportunity to pass into an aperture and the ends to be snipped.

The bean pods as they come from the field 65 are first sorted by any desired means into a number of lots of substantially uniform size. This is an important step of my process, since the beans as picked, especially for canning purposes, are of a number of sizes, from those which are very small to those which are fully grown. This is uniform practice in canneries and the assorting may be done by well-known mechanism or by hand. In general, there will be from three 70 to five of such sizes, which are ordinarily packed separately and are sold at different prices, the smaller beans bringing a higher price. The apertures of the support provided are adapted for use in a particular 75 lot of beans. That is, the smaller the beans the smaller the apertures in the supports for such beans necessarily will have to be. There must be, therefore, a separate support for each substantially similar lot of 80 bean pods. In practice I have found that ordinarily not less than three different sizes of aperture and different positioning members are required to care for the various 85 assortments of bean pods which come to the cannery from the field.

Various forms of support are practicable, but I have found that a rotatable cylinder which performs the double function of providing the apertured support and also of 90 lifting and turning and dropping the bean pods is effective and economical for the purpose.

One form of apparatus for carrying out the steps of my process is shown and described herein and is claimed in my co-pending application Serial Number 154,104, filed March 12, 1917, of which this application is a division. The drawings, illustrating this 95 form of apparatus are as follows:

Figure 1 is a side elevation of an apparatus embodying my process. Fig. 2 is an enlarged end elevation of the same with some parts broken away. Fig. 3 is a plan view of a portion of the interior of the cylinder showing the pod-positioning net or web. Fig. 4 illustrates the manner of 100 adjustably holding the pod-positioning nets in the cylinder. Figs. 5, 6 and 7 are fragmentary plan views on an enlarged scale of 105 110

2
portions of cylinders and positioning nets therein of different sizes for operation upon different assortments of bean pods.

A cylinder or drum 10 is supported by 5 angle iron bands 11 and 12 upon front and rear rollers 13 and 14 journaled in supporting stands 15 and 16. A ring gear 17 meshes with a drive pinion 18 on a driven shaft 19 journaled in supporting standard 10 16 by which the cylinder 10 is rotated at the desired speed. A funnel member 20 is connected by a chute 21 with a hopper 22 by means of which the bean pods are fed at the desired rate, first into the hopper 20 15 and thence into the body of the cylinder 10. As shown in Fig. 1 the cylinder is set at a suitable angle so that as the bean pods are rotated around and around with the cylinder they will travel toward the front or discharge end thereof, finally discharging upon the conveyer belt 23.

The cylinder 10 is preferably made of sheet metal and has formed therein a multiplicity of apertures 24, there being as many 25 of such apertures as can be formed of the desired size and leave the shell of the cylinder sufficiently strong to stand up and perform its shearing function. To add to the 30 strength of the cylinder and for the purpose of receiving the positioning nets or webs, hereinafter described, a multiplicity of ribs 25 preferably of inverted V-shape, as shown in Fig. 2, are secured longitudinally to the inside walls of cylinder 10. The facing 35 walls of said ribs are parallel and secured to these walls are frames 26 which carry a wire mesh 27, as shown in detail in Fig. 3, and which are thereby held spaced from the inner wall of the cylinder, as indicated in 40 Fig. 2. It is to be noted that the wire mesh 27 provides rectangular openings of much larger size than the openings 24 through the cylinder. Also, that spaces 28 and 29 on each side of the mesh 27 and between it and 45 the walls of ribs 25 are left open to permit bean pods which may get outside of the mesh to be freely discharged from the walls of the ribs as the same are moved upwardly. It is to be noted also that the frames 26 50 preferably have one edge thereof, as indicated at 30, curved in the direction of rotation of the cylinder so as to hold the bean pods from discharge until the same have been carried to or past the top of the cylinder, from which point they will tend to drop 55 longitudinally and will strike the meshes 27, and in going through the same will be positioned as indicated at 31 so that the ends thereof will pass into the apertures 24. The 60 frames 26 are adjustably connected to the ribs 25 by bolts 32 passing through slots 33 in said frames and into the ribs.

The apertures in the shell of the cylinder 10 are preferably formed square. As indicated in Fig. 5, the cylinder 10 has aper-

tures 34 of largest size co-operating with a mesh 35 of corresponding larger size; while in Fig. 6 the apertures in cylinder 10 indicated at 36 are smaller in size than those at 34 and co-operate with a mesh 37 of 70 smaller size than mesh 35; and the apertures 38 in cylinder 10, shown in Fig. 7, co-operate with a mesh 39 of still smaller size. These cylinders, having the several sizes of apertures and of mesh, are sufficient to take 75 care of the various assortments of bean pods resulting from any given picking.

Arms 40 and 41 are adjustably secured by bolt and slot connections 42 and 43 with the supports 15 and 16 and the respective 80 pairs of said arms carry shearing bars or knives 44 and 45 positioned in proximity to the outer periphery of the rotating cylinder 10, where said knives will engage the protruding ends of bean pods and snip them 85 off. I have shown two such knives, but do not desire to limit myself, as a greater or less number may be employed.

As shown in Fig. 1, the supporting stands 15 and 16 are of unequal heights so that the 90 axis of the cylinder or drum is depressed at a slight angle to the horizontal, which in conjunction with the rotation of the drum and lifting of the beans effect, the longitudinal travel of the pods through the machine. 95

As hereinbefore stated the first step of my process consists in assorting the beans, as they come from the vines, into a suitable number of lots each containing beans of substantially the same size, that is, beans which are of substantially the same thickness or have substantially the same cross sectional dimensions throughout. After the assorting, the apparatus herein described will efficiently carry out the further steps of my 100 process, in which the cylinder provides a perforated supporting member, the rotation of the cylinder and the lifter blades therein constitute means for presenting the pods to the perforations of the supporting member 105 which always is the lower part of the rotating cylinder, and the wire mesh constitutes means for acting upon the pods while they are moved or as they are presented to the supporting member to cause the engagement 110 with the supporting member to be with the ends of the pods. The rotation of the cylinder in conjunction with the co-acting knife bar provides means for snipping the ends 115 of the pods.

The advantages of my process will be apparent. The pods after having been sorted into lots of proper size may be continuously fed through the cylinder support having apertures and mesh work of the right size. 125 Each pod will be agitated and turned and dropped endwise many times in the course of its travel from its entrance into the cylinder to its discharge from the lower end thereof. This, in combination with the ac- 130

tion of the spaced mesh, will result in giving each end of every pod many opportunities to enter a perforation, with the result that few, if any, of the pods will reach the discharge end of the cylinder without having the ends thereof properly snipped. The apertures in the supporting member are each of a size to permit an end of a pod to pass sufficiently far through an aperture to 5 present the right part of said end to the snipping action of the bars or knives, but are small enough to hold the pods of any assortment from going farther than that. The provision of several agitating, turning 10 and snipping means having apertures and holding mesh of a proper size to operate upon the corresponding assortment of pods resulting from the first step of my process, insures that the pods will not be improperly snipped or portions of the beans wasted 15 thereby.

I claim:

1. The process of snipping bean pods which consists in operating upon several 20 previously assorted lots each containing pods of substantially the same thickness, by presenting each lot of pods to a separate supporting member, each of said members having therein a multiplicity of apertures of a size proportioned to the size of the pods presented thereto and of a different size for each member, acting upon the pods of each lot as they are presented to its member to cause the ends thereof to pass into the apertures of 25 such member and to have the part to be snipped protruding through said apertures, and snipping said protruding parts.

2. The process of snipping bean pods which consists in operating upon several 30 previously assorted lots each lot containing pods of substantially the same thickness, by acting upon each lot of pods to snip the ends of the same by a separate set of instrumentalities, each of which sets of instrumentalities is formed and proportioned in correspondence with the thickness of pods of 35 one lot to operate only upon pods of such lot.

3. The process of snipping bean pods which consists in operating upon several 40 previously assorted lots each lot containing

55 pods of substantially the same thickness, by presenting the pods of the several lots to a corresponding number of snipping devices respectively adapted to receive and hold individual bean pods of said several lots and to snip the ends thereof while held, and causing the bean pods of each lot to be held and snipped by its snipping device by repeatedly presenting the pods of each lot independently and causing said pods individually 60 repeatedly to move into engagement with the holding means of its snipping device.

4. The process of snipping bean pods 65 which consists in operating upon several previously assorted lots each lot containing pods of substantially the same thickness, by presenting the pods of the several lots to a corresponding number of snipping devices 70 respectively adapted to receive and hold bean pods of said several lots and to snip the ends thereof while held, and causing the bean pods of each lot to be held and snipped by its snipping device by repeatedly presenting the pods of each lot independently and causing said pods individually 75 repeatedly to move into engagement with the holding means of its snipping device, and acting upon the pods while so moved to cause such 80 engagement to be with the ends of the pods.

5. The process of snipping bean pods which consists in operating upon several previously assorted lots each lot containing pods of substantially the same thickness, by 85 presenting the pods of the several lots to a corresponding number of snipping devices respectively adapted to receive and hold bean pods of said several lots and to snip the ends thereof while held, and causing the 90 bean pods of each lot to be held and snipped by its snipping device by repeatedly lifting and turning the pods of each lot independently and causing the pods of each lot individually repeatedly to move into engagement 95 with the holding means of its snipping device after it has been lifted and turned, and acting upon the pods while so moved to cause such engagement to be with the ends of the pods.

In testimony whereof I affix my signature.
EDWARD J. VAUDREUIL.
